ARMSTRONG FREEMAN, OF LOWELL, MICHIGAN.

Letters Patent No. 70,429, dated November 5, 1867.

IMPROVEMENT IN CATTLE GUARD GATE.

The Schedule referred to in these Letters Patent and making part of the same.

TO ALL WHOM IT MAY CONCERN:

Be it known that I, ARMSTRONG FREEMAN, of Lowell, in the county of Kent, and State of Michigan, have invented certain new and useful Improvements in Cattle Guard Gates; and I do hereby declare that the following is a full and complete description of the same, reference being had to the accompanying drawings, making part of this specification, in which—

Figure 1 is a side view of the gate extended.

Figure 2 is a top view.

Figure 3, an end view of the same.

Like letters of reference refer to like parts in the different views.

A, fig. 1, is the gate, which consists of a number of slats, B, arranged and pivoted together at the points X, as shown in fig. 1, thus making an extensive and contractive gate which is operated as and for the purpose hereafter shown. This gate is pivoted a distance above the ground to a post, C, at the point a, and is furthermore supported upon a grooved wheel, D, traversing a rail, E, (fig. 3.) F F (fig. 2) are railroad ties, on which are laid the rails G G'. Along the outer side of rail G' is a rail, H, secured upon the ends of the levers I, (fig. 1,) said levers being pivoted to the stays J, upon which they vibrate, thereby allowing the rail G' to be raised upward and downward, as will hereafter be described. Projecting at right angles from the top of the levers are standards J', (fig. 1,) shored by the braces K. The upper ends of these standards are connected to levers K' by chains L. Said levers K' are pivoted to the top of the standards or posts L', (fig. 3,) and have a horizontal movement, their free ends crossing each other at the rear end of the gate, and against which they are drawn for a purpose hereafter shown. M (fig. 1) is a short post, to which is pivoted a standard, M'. The upper end of this standard is connected to the gate by links N. Projecting back from this standard is an arm, N', to which is attached a weight, O, whereby the gate is closed after being opened by the passing train. On the train passing over the section of the road exhibited in the drawing, the wheels strike upon and press down the side or movable rail H level to the tread of the line rail G', the effect of which is to draw the end of the standard J in the direction of the dotted line a'. This being connected to the levers K', draws the free end of them against the rear end of the gate, which causes it to draw up and back from its position across the track in virtue of the leverage exerted upon the slats composing the gate; the gate in construction being a succession of simple levers exerting their power upon each other from the fulcrum a to the front end of the gate. As the gate contracts, the arm N and weight rise up in direction of the dotted line b. The gate by this means is drawn from across the track, leaving it clear for the train to pass, which on having passed, and the weight of the last car rolled from off the side rail H, the weight O suspended from the arm N, and the weight O' on the end of the lever I, exerted upon the slat directly pivoted to the post C, and which is the first lever through which all the others are moved, causes an extension of the gate across the track, as shown in fig. 1, thereby shutting out cattle and other animals from the road; and so on, alternately, as the coming train rolls on to the rails G G', and pressing down the side rail H, the gate gathers back from off the road by the action of the levers K' exerted against the rear end of the gate, as above described, and again extended by the weights O O'. In order to facilitate the movement of the gate, and prevent any undue strain and sagging, the roller D, above referred to, is attached to the bottom of the gate, and upon which it rolls easily, and without restraint. The holes through which the pivots are inserted in the construction of the gate, are bushed with iron or any other suitable material, thereby reducing the friction and wearing of the gate, thus rendering it much easier in its operation, and more durable.

What I claim as my improvement, and desire to secure by Letters Patent, is—

1. The side rail H, lever I, chains L, and levers K, as arranged, in combination with the gate A, for the purpose and in the manner as set forth.
2. The gate A, and roller D, as arranged, in combination with the standard M', links N, and weighted arm N', in the manner and for the purpose herein described.

ARMSTRONG FREEMAN.
